UNITED STATES PATENT OFFICE.

JOSEPH J. WILLIAMS, OF CLEVELAND, OHIO.

TOY STEAMER.

1,370,572.

Specification of Letters Patent.

Patented Mar. 8, 1921.

Application filed February 21, 1920. Serial No. 360,541.

To all whom it may concern:

Be it known that I, JOSEPH J. WILLIAMS, a citizen of the United States, residing at Cleveland, in the county of Cuyahoga and State of Ohio, have invented certain new and useful Improvements in Toy Steamers, of which the following is a specification.

This invention relates to a self propelled toy boat and has for its principal object to provide a boat of the character described supplied with a steam motor sufficiently powerful to propel the same and which shall be hereinafter more fully described, and which will be substantially free from operating parts and which may be simply controlled to travel in a backward or forward direction. The means for accomplishing this being simple and so constructed as to preclude any possibility of becoming out of order.

Further objects of the invention are to provide a boat of the character described which will be cheap of manufacture, attractive in appearance and capable of being played with by children without any possibility of harm to themselves.

Further objects of the invention are in part obvious and will appear more in detail from the following description and claims.

Reference being had to the drawings wherein like reference numerals designate similar parts of reference throughout the various views, Figure 1 is a central section through a device constructed in accordance with the principles above set forth; Fig. 2 is a plan view, the stove or heating element being removed; Figs. 3, 4, 5 and 6 are sectional details of the reversing valve.

The device comprises a hull 1 preferably made of tin and so shaped as to permit of being stamped from a single piece of material thereby to provide a cheap and efficient construction. As is customary the stern has pivotally secured thereto a rudder 2 which may be adjusted by means of a tiller 3 and by means of which the boat may be caused to travel in a circle within a convenient receptacle filled with water.

Substantially amidships of the boat is placed a stove 4 provided with a chimney 5 and supporting within its lowermost part a receptacle 6 within which is placed a quantity of combustible material 7, and experience has proved that material known to the trade as "solid alcohol" is preferable although by means of a wick suitably secured

to the top of the container 6 other fuel may be utilized such as gasoline, benzine, alcohol, ether and the like.

The stove 4 is further provided with an opening 8 at one side thereof and into which a miniature boiler 9 is allowed to project and said boiler is supported upon the ends of two pipes 10 and 11, the pipe 10 terminating immediately upon its entry to the interior of the boiler and the pipe 11 projecting substantially to the middle thereof for a purpose to be hereinafter described.

It has been found by experiment that the device operates in a more efficient manner if one tube extends farther into the boiler than the other as shown. The reason for this is not understood, but the fact has been demonstrated by trial.

The opposite ends of said pipes are secured to a disk 13 which forms one-half of a valve member indicated generally at 14; the said member 13 is provided with a central bore 15 and two diametrically opposed ports 17 and 18. The remaining portion 19 of said valve member is likewise provided with a central bore 15^a and four diametrically opposed ports 17^a and 18^a which at the proper time communicate with the ports 17 and 18 in the valve member 13. The two members 13 and 19 are secured to each other by means of a pivot pin 20 which passes through the bores 15 and 15^a and is held in place by means of a spring 21, washer 22 and pin 23 and by means of said spring it will be seen that sufficient pressure is exerted between the two halves 13 and 19 at all times to keep the respective faces in positive contact with each other and make a substantially tight joint.

The valve member 14 together with the pipes 10 and 11 and the boiler 9 are conveniently supported by the pipes 17^b and 18^b which are conveniently secured to the valve member 19 and which communicates with their respective ports 17^a and 18^a.

Referring to Figs. 1 and 2 it will be seen that the pipes 17^b extend rearwardly from the valve member 14 and in substantially a straight line through the stern of the boat and to a short distance beyond and are so constructed as to straddle the rudder 2. These pipes shall hereinafter be referred to as the forward propelling pipes. The remaining pipes 18^b also extend rearwardly until such time as they project through the hull 1. At this point they are bent for

wardly and lie substantially parallel to the sides of the hull as indicated in dotted lines at 25 and these pipes shall hereinafter be termed the reverse pipes.

- 5 It will thus be evident that if the valve member 13 is rotated by means of the handle 26 and the ports 17 come in registry with the ports 17^a communication is established with the boiler in a way to permit 10 of a discharge therefrom through the pipes 10, 11 and 17 and if the discharge end of the pipes 17^b are beneath the water line 30 such discharge will cause the boat to be propelled in a forward direction. Likewise 15 if the member 13 is rotated so that the ports 17 and 18 register with the ports 18^a communication is established through the pipes 10, 11 and 18^b thereby to drive the boat in a reverse or rearward direction and due to 20 the fact that the member 13 is provided with but one set of ports communication with one set of ports in the member 19 prohibits communication with the remaining set.

In operation water is initially forced into 25 the boiler 9 through the pipes 17^b by a syringe or the like. The boiler is then heated until steam is generated therein and it is ejected through said pipes in the manner above described, the air confined in the 30 boiler being first driven out. The lower ends of the tubes are kept cool by the body of water, and this produces condensation of the steam in said tubes, which results in the formation of a vacuum causing the 35 water to flow upwardly in the tubes until it reaches the heated zone formed by the boiler and the upper parts of the tubes, and the water so introduced flashes into steam which produces an impulse and drives 40 the water out of the lower ends of the tubes. The steam then in the lower ends of the tubes condenses and the vacuum is formed again, and so the operation is repeated, the flashes into steam, the condensation, and the 45 inflow of water succeeding each other rapidly, and at each "flash" a propelling impulse is given by the forcible discharge of

the water from the lower ends of the tubes, which drives the boat forwardly.

It is evident that were it possible to initially fill said boiler with water but a single pipe might be utilized and for this reason at least two pipes are preferably employed and experience has proven that the operation is more successful if one pipe extends 55 farther into the boiler than the other although this is not necessary. Water will then flow in through one pipe and steam flow out through the other. It is also evident that the number of pipes may be increased together with the size of the boiler, and in this manner more power is obtained and while I have shown and described this particular construction I do not wish to limit myself in the construction of the same 60 further than is required by the state of the art or that which comes within the scope of the appended claims.

I claim:

1. A boat provided with a steam boiler, 70 a pipe communicating at one end with the boiler, a turning valve member to which the other end of the pipe is attached, a fixed valve member, coöperating with the turning valve member, and pipes extending from 75 said fixed valve member to the exterior of the boat, one of said pipes being directed forwardly and the other rearwardly and so arranged that the pipe connected with the boiler may be registered with either of the 80 last mentioned pipes.

2. A boat provided with a steam boiler, and a pair of pipes communicating with the boiler and extending through the hull of the boat and opening below the water line, 85 one of said pipes projecting into the boiler to a greater extent than the other.

In testimony whereof I do affix my signature in presence of two witnesses.

JOSEPH J. WILLIAMS.

Witnesses:

JOHN A. BOMMHARDT,
ROBERT L. BRUCK.
